UNITED STATES PATENT OFFICE.

WARREN S. EATON, OF PLAINFIELD, NEW JERSEY.

AEROPLANE.

1,290,136.

Specification of Letters Patent.

Patented Jan. 7, 1919.

Application filed July 20, 1917. Serial No. 181,820.

To all whom it may concern:

Be it known that I, WARREN S. EATON, a citizen of the United States, residing at Plainfield, in the county of Union and State 5 of New Jersey, have invented certain new and useful Improvements in Aeroplanes, of which the following is a specification.

This invention, which generically has reference to improvements in aeroplanes, is 10 more particularly designed for presenting improved means for stabilizing and in other respects controlling the aeroplanes, while in flight.

As is well known in air craft of the type 15 stated, when flying, the machine is kept under balance or upright by flexing or warping the ends of the planes or otherwise increasing the angle of incidence of the plane surface on the air for producing the desired 20 lateral direction, with or without the co-operation of rudder control.

One of the objects of my invention is to provide certain improvements in air craft, 25 wings or planes past which the air flow from the back to the front is capable of variation by the aviator, while flying, and by which the said air flow may be quickly and positively effected with a degree of certainty in adjusting the planes for balancing 30 the machine, especially at times when it is subjected to unexpected gusts of wind from any direction.

Another object of my invention is to provide in an aeroplane, certain improvements 35 in the nature of supplemental planes or wings that coöperate with the main planes or wings and are capable of being quickly and positively manipulated by the aviator for effecting the desired stabilizing or lateral control of the machine, without bending, warping or in any manner changing the condition of the main wings or planes, in order to vary the angle of incidence of 40 portions of the main plane surfaces to produce the required turning movement of the plane about the longitudinal axis of the machine, and for reducing head resistance to the minimum.

With other objects in view that will hereinafter appear, my invention embodies, in 50 an aeroplane structure, the peculiar combination and novel arrangement of the parts presently fully explained, specifically point-

ed out in the appended claims and illustrated in the accompanying drawings, in 55 which:

Figure 1 is a top plan view of an aeroplane structure that embodies my invention.

Fig. 2 is a front elevation thereof, the supplemental wings or planes being shown in 60 the central or neutral position.

Fig. 3 is a side view of the machine.

Fig. 4 is a longitudinal section of one of the main planes and the coöperating supplemental wing or plane, the latter being 65 shown positioned in the middle or neutral position.

Fig. 5 is a similar view, the supplemental plane being indicated at the elevated position for decreasing the lift.

Fig. 6 is a similar view, the supplemental wing or plane being positioned for increasing the lift, the lines of air pressure when the wing is thus positioned being indicated in broken lines, like indications also appearing on Figs. 5 and 6.

Fig. 7 is a perspective view of one of the supplemental wings or planes, a portion of the main plane to which it is attached and portions of the operating gear.

Fig. 8 is a longitudinal section taken on the lines 8—8 on Fig. 1 and illustrates diagrammatically the wing or vane shifting gear.

Fig. 9 shows the lever connection that is 85 mounted in the cock pit.

In the drawings, I have shown a simple type of aeroplane in which is embodied an upper plane 10 and a lower plane 17 suitably braced to form a rigid plane frame, by 90 vertical standards, lateral braces, and guy rods, as is clearly shown in Figs. 2 and 3.

In my construction of aeroplane, the upper or main plane 10, the longitudinal shape of which is best shown in Figs. 4, 5 and 6, 95 has attached to each end thereof, a supplemental plane or wing section, hereinafter termed the deflector planes 1—1, and each of the said deflector planes 1—1 is of such dimensions as may be found necessary.

100 11 denotes the cock pit, 12 the body, 13 the rudder, 14 the stabilizer, 15 the elevator, 18 the fin and 16 the propeller.

Since the deflector planes 1—1 at both 105 ends of the main plane 10, are constructed and operated alike, a detail description of

one of the deflector planes and the gear connections that operatively join it with the main plane will be sufficient.

The gear connections, operable by the aviator, comprise a rock shaft 4 which extends transversely of the body 12, suitably journaled along the front edge of the main plane 10, extends approximately the full width thereof, as is best shown in Fig. 1, 10 from which it will also be seen that midway its ends, the rock shaft carries a pair of cranks 40—41, one 40 of which operates the deflector plane at one side, and the other 41 operates the deflector plane at the other side 15 and the said cranks 40—41 are each joined by a link connection with a rocking lever 7 suitably mounted on the body and connected to a control lever 9 located in the cock pit 11 for being conveniently handled by the 20 aviator.

The deflector plane 1 is so connected with the main plane 10 that it moves parallelly to itself at all times as it rises or falls, when shifted by the aviator, and to that end, 25 a connection is provided which is preferably as follows:—The said deflector plane 1 has a pair of longitudinal slots 1^a—1^a that register with a pair of like slots 10^a—10^a in the front edge of the main plane 10.

30 In each of the two alining slots 1^a—1^a move a pair of combined connecting and bracing levers 3—30, one of which is fixedly connected to the rock shaft 4 and has a pivotal connection at the other end 31 with 35 the deflector plane 1. The other lever 30 is pivotally connected at the outer end to the deflector plane 1 and its inner end 32 is likewise connected to the main plane 10, the several pivotal connections of the brace lever 40 with the rock shaft 4 and the planes 1 and 10 being normally in a neutral position as shown in full lines on Fig. 4, and by reason of such pivotal relation of the brace levers with the plane 1 and the said shaft 4, the 45 plane 1 is maintained in a position parallel to itself as it is vertically shifted, and by reason thereof, the horizontal line of travel of the machine is not disturbed during the operation of shifting the deflector plane 1 up 50 or down for effecting the desired lateral stabilizing or control. Any other parallel motion connection may be used.

From the foregoing taken in connection with the drawings, the construction of my 55 invention, the manner of its operation and the advantages thereof will be readily apparent to those skilled in the art to which my said invention appertains.

It will be noticed, the deflector planes 60 1—1 in my construction extend along the main plane but a short distance from each end, and by reason thereof little or no head resistance beyond that usually encountered is thereby created.

65 When the machine is in flight, there is air

pressure that banks against the lower surface of the main planes, as indicated by the arrows on Fig. 4, assuming the deflector plane 1 to be now in the neutral position.

Should the machine tip to either side, 70 the said deflection from the horizontal plane is corrected by manipulating the lever 9 so that the deflector plane on the downwardly tipping side is dropped in a plane below the neutral, as indicated on Fig. 6. 75

The pressure of air on the under face of the downwardly tipping side of the plane is now increased (and the pressure on the top side is decreased) as indicated by the arrows on Fig. 6, and the pressure on top of 80 the planes at the other or higher side, is relatively increased (and the pressure on the bottom side is decreased) by reason of the deflection of the air pressure, as indicated by the arrows on Fig. 5, and further by 85 reason of the manner in which the deflector planes are geared up with the aviator's lever, the restoring of the equilibrium to the machine can be rendered gentle and gradual under variable manipulations of the avia- 90 tor's lever 9.

By varying the position of the deflector planes to the angle of incidence of the sustaining plane to the air flow is changed, thus either increasing or decreasing the lift 95 on that portion of the plane affected without in any way changing any portion of the main sustaining plane with regard to the other portions thereof.

In the drawings is shown in diagrammatic 100 manner, a practical arrangement of an airplane in which my invention is embodied but I desire it understood that the exact details may be varied or modified from that shown in the drawings without departing 105 from my invention as comes within the scope of the appended claims.

What I claim is:

1. In an air craft, the combination with a main plane; of a deflector plane located at 110 each end and in front of the main plane and aviator controlled gearing for maintaining the said deflector planes in a neutral position in the plane of the said main plane, and any planes parallel to its neutral position above 115 and below the said main plane.

2. In an air craft, the combination with a main plane; of a deflector plane located at each end and in front of the main plane, an aviator controlled gear for maintaining 120 the said deflector planes at all times in a plane parallel to their neutral position with the main plane and for simultaneously imparting movement to the said deflector planes above and below the main plane.

3. In an air craft, the combination with a main plane; of a deflector plane located at each end and in front of the main plane, an aviator controlled gear for maintaining 125 the said deflector planes at all time in a plane 130

parallel to their neutral position with the main plane and for simultaneously imparting movement to the said deflector planes above and below the main plane, the said deflector planes being relatively connected for moving in harmony and in alternate direction.

4. In an aeroplane, the combination with the main plane, a horizontally disposed deflector plane located at each end and in front of the main plane, said two deflector planes being connected for operating in harmony in alternate direction to positions above and below the main plane and gearing controlled by the aviator for adjusting the said deflector planes parallel to themselves in unison without disturbing the horizontal direction of flight of the machine.

5. In an aeroplane, the combination with the main plane, a horizontally disposed deflector plane located at each end and in front

of the main plane, gearing controlled by the aviator for adjusting the said deflector planes parallel to themselves without disturbing the horizontal direction of flight of the machine, said gearing including a rock shaft mounted across the main plane, the said shaft having a pair of cranks, one for each deflector plane, and brace levers pivotally connecting the main and the deflector planes and other levers pivotally connecting the rock shaft and the deflector planes.

6. An air craft main plane having attached means for deflecting the air flow past the outer ends thereof, said means consisting of a plane surface shiftable in a plane parallel to itself and without changing the horizontal direction of flight of the said main plane during the shifting of the said deflecting means in planes above or below the main plane.

WARREN S. EATON.
